UNITED STATES PATENT OFFICE.

FRANK D. LA VALLE, OF NEW YORK, N. Y.

GARMENT-FASTENER.

1,383,129.

Specification of Letters Patent. Patented June 28, 1921.

Application filed November 11, 1920. Serial No. 423,433.

To all whom it may concern:

Be it known that I, FRANK D. LA VALLE, a citizen of Italy, and a resident of the city of New York, borough of the Bronx, in the 5 county of Bronx and State of New York, have invented a new and Improved Garment-Fastener, of which the following is a full, clear, and exact description.

This invention relates to separable fasteners and more particularly to garment fasteners especially designed for use on ladies' underskirts.

The invention contemplates and seeks for its main object to provide a simple and effective fastening device of the character described which is readily and quickly operable to effect the fastening or unfastening of a garment, or other article to which it is applied.

Another advantage and object featured by the invention is the strength and durability of the construction, the simplicity in the manipulation of the same, and the cheapness with which it may be manufactured and 25 attached to the garment.

With the above recited and other objects in view, some of which will appear hereafter, reference is had to the following specification, the appended claims and the accompanying drawings forming a part of this 30 application, in which;

Figure 1 is a view of a garment equipped with the fastener showing the same in closed position.

Fig. 2 is a fragmentary enlarged view thereof.

Fig. 3 is a similar view illustrating the device unfastened.

Fig. 4 is a sectional view taken approximately on the line 4—4 of Fig. 3.

Fig. 5 is a perspective view of one of the members prior to its application to the garment.

Referring to the drawings by characters of reference, S designates a skirt provided with the usual gathered elastic waist band B, having a placket P.

The fastener preferably includes a pair of identically constructed separable members 10 each of which comprises a base 11 constructed of a strip of metal and preferably provided with an integral offset hooked portion 12 which extends from one of the longitudinal edges adjacent one of its ends 50 and is bent outwardly and downwardly to dispose the free extremity thereof in spaced

relation to the base. The base is provided with means for securing the same to the garment, which preferably consists in providing integral tubular rivets 13 drawn therefrom as illustrated. In applying the fastener to a garment the base 11 of one of the members 10 is secured to the outer surface of the waist band B adjacent the edge of the under flap of the placket P, with the hooked portion 12 thereof disposed outwardly from the waist band, and the base of the other member 10 is secured to the inner face of the waist band adjacent the edge of the outer flap of the placket. By this arrangement when the fastener is closed, the hook 12 of each member 10 will embrace and coact with the base and portion of the waist band to which the other member is secured, to prevent lateral displacement of the members, and the confronting side edges of the hooked portions will contact and coact with each other to prevent longitudinal relative separation of the flaps of the placket.

To fasten the skirt, the hooked portions 12 of each member is simultaneously engaged over the base 11 of the opposite member adjacent the ends remote from the hooked portion and the portion of the waist band to which said bases are secured: the members are then moved relatively to advance the hooks 12 toward each other until their confronting ends are in contacting engagement. To unfasten the garment the members 10 are moved relatively to separate the hook members 12 from each other and then disengaged from the bases 11 and the portion of the waist band to which said bases are secured. The hook while described and illustrated as forming an integral part of its base, may be constructed of a separate piece of material and secured thereto and if desired the rivets may also be made as separate elements.

While there has been illustrated and described a single and preferred embodiment of the invention, no limitation is necessarily made thereto, as it is to be understood that the right is reserved to embodiments other than those actually shown herein, to the full extent indicated by the general meaning of the terms in which the claims are expressed, and by variations in the phraseology of the same.

I claim:

1. A separable fastener comprising a plurality of members each provided with

5 a base having an offset portion, the said offset portions adapted for interengagement with the bases when in closed position for securing the same against lateral separation and for interengagement with each other whereby to limit relative longitudinal movement.

10 2. A separable fastener comprising a plurality of members, each provided with a base having an offset hooked portion, the said offset hooked portion of one member adapted for interengagement with the base of the other member when in closed position, as and for the purpose specified.

15 3. A separable fastener comprising a plurality of members including a base provided with an offset portion constituting laterally spaced hooks, the hooks of each member adapted for inter-engagement with the body portion of the other member when in closed position for securing the members against lateral separation, said hooks adapted to engage and contact with each other to limit the relative longitudinal movement of

20 25 the members in one direction.

4. A garment fastener including a plurality of separable members, each comprising a base having a hooked portion on one of its sides adjacent one end thereof, said base adapted for securement to a garment, each of said hooks adapted to embrace and co-act with the base of the other member to secure the members against lateral displacement, said hooks adapted to engage and co-act with each other to limit relative longitudinal movement, in one direction.

5. A garment fastener including a pair of identically formed members, each comprising a base adapted to be secured to a garment and an integral hook provided on said base adjacent on end thereof and having its free extremity overlying said base in spaced relation thereto, said hooks adapted to embrace and co-act with the bases of the other member and with one another to secure the members against lateral displacement and longitudinal separation in one direction.

FRANK D. LA VALLE.
